LAUNDRY MACHINE

James B. Kirby, West Richfield, Ohio, assignor to
Industrial Improvements Incorporated, Cleve-
land, Ohio, a corporation of Ohio

Original application November 3, 1927, Serial No.
230,753. Divided and this application June
17, 1929. Serial No. 371,544

5 Claims. (Cl. 68—15)

This invention relates to laundry machines and has for its object the provision of improvements in clothes washing machines applicable primarily to domestic washing machines, where-
5 by the construction is simplified, the number of parts reduced, the cost of important parts de-
creased, and improved certainty and safety of
operation secured. The invention finds its
greatest advantages in connection with those
10 washing machines wherein the clothes are freed
from adherent liquid by a centrifugal extractor.

Certain washing machines, mostly confined to an earlier day, were operated hydraulically from the municipal water pressure, but have proven
15 unsatisfactory and largely gone out of use for two reasons: variations of water pressure which precluded successful operation at some places either always or occasionally; and municipal dis-
favor due to excessive use of water. These hy-
draulic machines have been largely replaced by
20 electrically driven machines which wholly over-
come the first noted objections but entail other
peculiar drawbacks chiefly: (a) the necessity of
some more or less complicated mechanical speed-
reducing, power-transmitting and motor-trans-
25 forming appliances to adapt the regular rotation
of the motor shaft to the purpose in view; (b) the high cost of the low speed motor which must
be used if the mechanical problems are kept in
proper bounds; (c) the positive nature of the
mechanical type of drive coupled with the increase
30 of mechanical advantage due to speed reduction
renders such devices potentially dangerous to
unskilled persons.

I have found that by a new and peculiar com-
bination of the two systems, namely electric op-
eration and fluid-pressure, I can avoid the de-
fects of both, avoiding all uncertainty of pres-
sure, all waste of water, all complicated gearing
40 and much of the previous danger to unskilled
persons, while enabling the use of a smaller and
cheaper high-speed motor in place of the heavy
slow-speed motor heretofore employed. Other
objects and advantages of my invention will be-
45 come apparent as the description proceeds. This
application is a division of my former application
filed November 3, 1927, Serial No. 230,753.

In the drawings accompanying and forming a
part of this application I have shown certain il-
50 lustrative embodiments of my inventive idea.
Fig. 1 is a vertical sectional view through the
essential parts of a simple type of washing ma-
chine containing my improvements; Fig. 2 is a
vertical sectional view corresponding to the line
55 2—2 of Figs. 1 and 3; Fig. 3 is a bottom plan

view of the machine; Fig. 4 is a longitudinal sec-
tional view through the dasher oscillating cyl-
inder; and Fig. 5 is a detailed view of the control
valve. Fig. 6 is a vertical sectional view through
a modified washing and extracting machine; Fig. 60
7 is a top plan view of the device shown in Fig.
6, and Fig. 8 is a cross sectional view correspond-
ing to the line 8—8 of Fig. 6. Fig. 9 is a vertical
sectional view of another modified type of ma-
chine containing my improvements; Figs. 10 and 65
11 are horizontal sectional views correspond-
ing to the lines 10—10 and 11—11 respectively of
Fig. 9 and looking in the direction of the arrows;
and Fig. 12 is a sectional view corresponding to
the line 12—12 of Fig. 11. Fig. 13 is a vertical 70
sectional view through another type of machine
embodiment my improvements; Fig. 14 is a detail
elevation of the machine shown in Fig. 13; Fig.
15 is a horizontal sectional view corresponding to
the line 15—15 of Fig. 13 looking upwardly; and 75
Figs. 16 and 17 are details respectively of pump
rotor, and turbine rotor illustrated in Fig. 13;
Fig. 18 is a sectional view on the line 18—18 of
Fig. 13; and Fig. 19 illustrates another machine
embodiment my improvements; Fig. 20 is a verti- 80
cal sectional view of the modified form of pul-
sating hydraulic washing device employed there-
in; Fig. 21 is a partial view on the same section
as Fig. 20 showing the parts in different posi-
tion; Fig. 22 is a sectional view corresponding to 85
the lines 22—22 respectively of Fig. 21; and Fig.
23 is a sectional view on the line 23—23 of Fig. 20.

The device illustrated in Figs. 13 to 17 inclusive are the identical devices illustrated in my former application Serial No. 614,080, filed Janu- 90
ary 22, 1923, and to this extent the present applica-
tion constitutes a continuation of said earlier
case.

The combined washing and extracting machine
illustrated in Figs. 1 to 5 inclusive of this applica- 95
tion exhibits a casing formed with two upright
compartments, 1 and 2, for washing and extract-
ing, respectively. In its preferred form said cas-
ing comprises an upright sheet metal wall 3
conforming to the major portion of a cylinder 100
intersected by the upright wall 4 of the other com-
partment which is itself generally partly cylindri-
cal at least, there being a third upright wall 5
located between the two compartments and con-
stituting a common partition extending from one 105
intersection to the other of said vertical walls.
Seamed to the lower edge of said side walls and
partition wall is a bottom plate 6 mounted on a
horizontal frame 7 carried by legs 8.

Mounted in vertical position in the external 110

angle between the side walls 3 and 4 at one side of the casing is an electric motor 10 whose shaft 11 depends therefrom and extends loosely into an upright pipe 12 at the bottom of which is a pump 5 casing 13 in which is a pump rotor 14 carried by said shaft. The outlet conduit 15 from this pump leads to a suitable control-valve, which in the present embodiment comprises a rotatable turning-plug 16 fitting in a hollow casing 17 and provided with an operating rod 18 connected to a handle 19. The conduit 15 leads to the bottom of the casing 17 and is hence in constant communication with the hollow interior 20 of the valve member 16, the side of which is formed with a port 21 adapted to be brought into register with one of the three ports 22 with which the side wall of the casing 17 is formed. Leading from these ports are three conduits 25, 26, and 27. The conduit 25 leads to a fluid-pressure operating device for actuating the clothes washing mechanism; the conduit 26 leads to a hydraulic device for actuating the extractor; while the conduit 27 consists preferably of hose attached to a nipple 28 on the valve casing and enabling the liquid to be discharged at any desirable place.

The washing mechanism is of what I term the fluid-pressure operated rhythmically operating type, in which expression I include all fluid-pressure operated devices whereby the clothes are periodically or intermittently, agitated or stirred, either directly by an intermittent hydraulic discharge or indirectly by an oscillating or reciprocating mechanical device actuated by fluid pressure. Within these limits the washing mechanism may take any suitable or desired form and in Figs. 1 to 4 inclusive, the washing device consists of an oscillatable dasher, comprising a circular metal plate 30 formed with one or more upright vanes 31, carried by an upright rock shaft 40 32 journaled in a sleeve 33 carried by the frame 7 and projecting into the bottom of the compartment 1, the lower end of the shaft being provided with a pinion 34 meshing with a rack 35. This rack is operated by means of a reciprocating hydraulic motor which in its present form, as illustrated in Fig. 4, comprises the following parts:

36 denotes a cylinder having at one end a packing box 37 in which fits slidably a piston rod 38 connected to the piston 39. Secured to the end 50 of the cylinder opposite the packing box is the valve mechanism which comprises a cylinder head 40 cored to form two chambers 41 and 42 separated by a web 43 and formed, respectively, with the inlet port 44 and outlet port 45. Opposite faces of said cylinder head are also formed with aligned pairs of openings 46, 47, and 48, 49, one pair for each chamber, and cooperating with said pairs of openings are the valve members 50 and 51, respectively, which are connected by a yoke 52 so as to move together. The valve member for the inlet chamber 41 has the valve heads inside of that chamber and work outwardly, while the valve heads for the outlet chamber are formed outside of that chamber and work inwardly. Secured to the yoke 52 is an operating rod 53 projecting through a hole 54 in the piston into a hollow bore 55 in the piston rod and terminating in a head 56, said rod being surrounded by a cushion spring 57 at each side of the piston. A longitudinal conduit 58 leads from the openings 47 and 49 to the opposite end of the cylinder. The conduit 25 is connected to the inlet port 44, while the outlet port 45 is connected with a conduit 60 leading to the inlet of the pump chamber 75 and also to an upright open stand pipe 61 suitably

located in some convenient part of the apparatus as for example inside the compartment 2 near one end of the partition 5. This stand-pipe accordingly constitutes a reservoir for the liquid in circuit to compensate for minor irregularities in movement between the pump and the pistons.

The extractor and also the turbine that drives it may also take any one of a great many forms. In the embodiment shown in Fig. 1 the extractor comprises a hollow frusto-conical container 62 larger at the bottom than at the top, formed near the bottom with discharge apertures 63, and having in the center of its bottom a hollow boss 64 rising into the container and tightly receiving the vertical shaft 65 which is rotatably sleeved in the vertical bearing 66 secured to the casing 7 and rising into the compartment 2. Secured to the lower end of the shaft 66 is the rotor 67 of a suitable turbine whose casing 68 is formed with an inlet connected to the conduit 26 and an outlet connected by a pipe 69 to the bottom of stand-pipe 61 and thence to the pump 13.

For washing purposes the compartment 1 is filled with washing liquid to the best washing level, which is preferably defined by a row of apertures 70 formed in the wall 5. The standpipe 61 is also filled with suitable liquid, preferably clean water, until it overflows at the overflow opening 71 provided therefor. The only reason for prolonging the standpipe 61 above the hole 71 is to facilitate filling the same, and the only reason for the hole 71 is that, being located below the top of pipe 12, it prevents accidental overflowing of the latter which would wet the floor. The motor 10 may be of any design which is properly mated to the pump but one advantage of the peculiar vertical mounting without stuffing box is that instead of the usual 1725 R. P. M. it can successfully be operated at a much higher speed, so that the necessary power can be obtained by a smaller and less expensive motor. If the valve 16 be so located that no port is open the water merely circulates in the pump chamber without doing any harm. When the valve is moved to connect the pump to conduit 25 the water passing through the inlet chamber 41 enters the cylinder 36 by way of whichever opening 48 or 49 is unobstructed, the contents of the opposite end of the cylinder being discharged through whichever outlet opening 47 or 46 is unobstructed. Arrived at the end of its stroke the piston compresses one of the springs 57 until the tension produced thereon is sufficient to overcome the hydraulic pressure on the face of whichever valves are closed, whereupon the spring is suddenly released, moving the valve yoke to the opposite limit of its movement and reversing the liquid flow through the cylinder. As a result the agitator is oscillated at a fixed speed dependent upon the pressure of the liquid, the size of the cylinder, and the diameter of the piston. Any obstruction to its movement does little damage because of the fact that the pump is an impulsive one. The standpipe 61 constitutes a reservoir to compensate for inequalities in the liquid flow at different parts of the stroke. Towards the end of the washing a few additional dipperfuls of water are thrown into the compartment 1 to cause scum to be washed through the apertures 70 into the extracting compartment, after which the clothes are transferred to the container 62 and the valve 16 moved to open the port which leads to the conduit 26. By proper arrangement of valve ports it is possible to operate both the washing device and the extractor simultaneously, although 150

this requires a larger pump and a more expensive motor than suffices otherwise. It is also obviously possible to combine the standpipe 61 with the compartments 2 or 1 and thereby employ the latter as a reservoir and use in the hydraulic devices the same liquid that is employed for washing.

An arrangement including these modifications is illustrated in Figs. 6, 7, and 8 which show a 10 casing formed with two upright compartments 1^a and 2^a for washing and extracting respectively. Said casing here comprises upright sheet metal walls 3^a and 4^a conforming to the major portions of two equal sized cylinders which intersect symmetrically forming vertical solid angles at the two sides, the two compartments having an upright common partition 5 as before, and a bottom plate 6, frame 7, and legs 8. Parts 10 to 28 inclusive appear as before. In this embodiment, 15 however, the washing mechanism comprises two jet-nozzles 75, 75 submerged in the liquid-holding portion of the compartment 1^a and connected to ports 76, 76 formed at opposite ends of the slide-valve-chamber 77 which is located crosswise along the lower margin of the partition 5. Located in this casing is the slideable valve member 78 connected by a lever 79 to a pitman 80 articulated to a worm wheel 81 which meshes with the worm 82 on the shaft 11.

20 The centrifuge in this embodiment comprises a foraminous container 62^a provided with an upstanding vertical axial shaft 83 terminating in a spherical ball 84 received in a suitable socket 85 carried by the bracket 86. The bottom of the basket is formed with turbine blades 67^a cooperating with jet nozzles 88 carried by the conduit 26. Owing to the fact that the centrifuge container swings freely from the point 84, I have shown two jet nozzles 88 located 180° apart to 25 avoid any bodily displacement of the centrifuge. The extractor chamber 2^a here takes the place of any stand-pipe and is formed with a drain opening 89 from which the conduit 60^a returns the liquid to the pump.

30 Sufficient washing liquid is introduced to fill the compartment 1^a, and also to maintain at all times at least a shallow layer in the compartment 2^a. As the motor and pump are operated the slide valve 78 is reciprocated to alternately open and close the ports 76, and when the valve 16 is also properly set a forceful stream of water is caused to issue alternately from the jet nozzles 75—75, agitating the clothing and removing foreign matter therefrom, while scum and floating impurities are washed through the openings 70 but remain in the compartment 2^a, since the return to the pump leads from the bottom of that compartment. Further adjustment of the valve handle 19 directs the flow of water to the 35 turbine blades 67^a which causes rapid rotation of the centrifuge; while still further adjustment of the valve handle causes ejection of the liquid contents of the machine through the hose 27.

In Figs. 9 to 12 inclusive I have shown my 40 improvements as applied to that kind of washing machine in which both washing and extracting take place in the same container. In this form of the invention I have shown a casing 1^b having a single upright cylindrical compartment carried by a frame 7 having legs 8, the frame having a rigid, upright, hollow sleeve 90 projecting a substantial distance upwardly into said compartment. Parts 10 to 26 inclusive are the same as before, excepting that in the present embodiment 45 the shaft 11 is provided below the pump 13 with an extension 11^a carrying a second rotor 91 inside a second pump casing 92 whose inlet communicates with the bottom of the casing 1^b through a pipe 93 which can be closed by a stopper 94 carried by an operating rod 95.

50 Rotatably journaled on the exterior of the upper end of the sleeve 90 is a hollow hub 96 to the lower end of which is tightly secured the bottom 97 (in this case the double bottom) of the combined washing container and extractor. The sides 98 of this extractor-container are suitably joined to the bottom 97 and are preferably slanted gradually outwardly to a point between top and bottom, but nearer top than bottom, where they are provided with one or more rows of discharge apertures 99, said container being imperforate below that point. Above the level of these apertures the diameter of the container is preferably decreased somewhat and the upper edge is preferably provided with a stiffening 55 rim 100.

The hub 96 is rotatable on the sleeve 90 and the bottom of the container is formed with turbine blades 67^b surrounded by a casing 68^b, here carried by the sleeve 90, and provided with a 60 drainpipe 69^b which leads to the lower end of the pipe 12, which in this embodiment takes the place and serves the functions of a standpipe or reservoir. The conduit 26 terminates in a nozzle 88 located in operative relation to the blades 67^b.

65 Journaled in the sleeve 90 is an upright rock shaft 101 having its upper end formed as at 102 for the reception of the socket 103 of the dasher which has a cylindrical-body portion 104 terminating at its lower end in a circular disk 105 overlying the bottom of the container and formed with suitable blades 106—107 according to any desired pattern. Secured to the lower end of the shaft 101 is a hydraulic oscillating device of any suitable kind which in the present embodiment 70 consists of a kind of segmental pump. This comprises a hollow member having a cylindrical side wall 110 terminated by circular end walls 111—112 one of which is removable. Journaled axially of this side wall is the shaft 101, provided at one 75 side with the radial blade 113 which sweeps about the wall. Interposed between the walls 111 and 112 at one point is the hollow valve box 114 separated by partition 115 into two chambers which communicate respectively with ports 116, 117 formed in the wall 110. Mounted in this valve box are valves 50^a—51^a, respectively, generally similar in construction and mode of operation to the valves 50 and 51 illustrated in Fig. 4, except that instead of providing the valves 80 with an operating yoke I have here illustrated the two sides of the piston 113 as provided with leaf springs 120 which, upon reaching the end of each oscillation, shift the valves and reverse the direction of motion in the same manner as described in connection with Fig. 4. The conduit 25 is connected with the port 117 which leads to the inlet valve chamber, while the port 116 communicating with the outlet valve chamber joins the pipe 69^b which returns to the pump. There 85 is no connection from the shaft 101 to the tub but only to the dasher. During the operation of the dasher the tub is at rest, supported by the top of the sleeve 90; during the rotation of the tub by the turbine 67^b the shaft 101 is at rest 90 although the dasher is best removed. The outlet port of the pump 92 is connected to conduit 121 which overhangs the washing container so as to produce, during the washing operation, a constant circulation of liquid which in conjunction 95

with the agitation of the dasher causes all floating scum to be washed through the apertures 99 and deposited in the casing where it is left. The employment of two separate pumps enables the complete separation of the washing liquid from the working fluid, the vertical pipe 12 acting as a reservoir to take care of different amounts of liquid required at different parts of the stroke of the piston, but it is possible to use only a single pump and employ the washing liquid in the operating devices as already described. Also it is possible to locate both pump and turbine inside one and the same chamber as will next be described.

In Figs. 13 to 17 inclusive I have shown the identical washing machine set forth in my application filed January 22, 1923, Serial No. 614,080. This comprises an upright cylindrical casing 1^a carried by the frame 7 and legs 8, and bolted to this frame concentrically with this casing is the casing 130 of a centrifugal pump having at its upper margin a circular flange 131 tightly applied to the bottom of the casing, this bottom being cut away inside the flange to permit free access to the pump chamber. Leading from the periphery of this pump chamber is an outlet pipe 132 which extends horizontally to the edge of the casing 1^a at which point it is provided with an upturned neck 133 and a side branch 134. Secured to the side branch is a hose or waste pipe 28 and located inside this branch is a waste valve 135 of any suitable type connected to an operating handle 136 which projects to some point where it can conveniently be grasped. Swiveled to the branch 134 is an upright pipe 137 which passes through a suitable collar 138 secured to the tub rim and terminates in an overhanging spout 139.

Secured inside the casing bottom opposite the flange 7 is a ring 140 to which is secured a spider 141 having an upwardly extending central boss 142. Secured to the bottom face of the pump casing 130 are a plurality of arms 143 to which is attached an electric motor 10^a having a vertical shaft 144 attached by the flexible joint 145 to the pump shaft 146 which enters the pump casing by way of the packing gland 147 and has connected thereto a suitable impeller shown in section in Fig. 16. In its present shape this impeller comprises a flat circular plate 148 having a central hub 149 receiving the shaft 146, and a plurality of blocks 150 carried by the upper surface of this plate and spaced from the hub to form a central chamber and also spaced from each other to form a plurality of spiral outlet passageways 151. I have shown the tops of these passageways as covered by a shroud plate 152, and the interior of the pump casing as formed with a circular rib 153 which projects rather close to the edge of this shroud plate and defines a circulation channel which communicates with the outlet pipe 132.

Journalized in the boss 142 is a vertical shaft 155 above the shaft 146 and having secured to its lower end a suitable turbine rotor one form of which is shown in Figs. 13 and 17. In this particular embodiment the rotor comprises a circular face plate 156 having on its lower surface a plurality of curved vanes 157 these vanes being presented toward the upper surface of the impeller, and the surface of the plate 156 being shaped to define a smooth sweep into the central cavity of said impeller. The periphery of the plate 156 is spaced from the ring 140 a sufficient distance to permit free ingress of liquid from the casing interior.

The shaft 155 is formed at its upper end with a prismatic portion 158 which projects above the boss 142 for the reception of the rotating tub in which are placed the articles to be washed. This tub comprises a bottom 160 and side wall 161, the whole terminating in a top flange 162 located slightly below the top of the casing 1^b. This side wall is preferably formed with an external bulge intermediate its top and bottom, the bulging portion being provided with a plurality of liquid discharge apertures 163. I also find it advantageous to form the sides of the tub with vertical corrugations as shown at 164 in Fig. 18, these being so arranged as to intersect said discharge openings 163. This arrangement keeps the clothes from packing tightly against the walls thereby always permitting free discharge of the liquid during the spinning operation, the side wall being preferably imperforate below the level of the apertures 163 so as always to maintain sufficient liquid in the tub for the washing operation. This corrugated metal also facilitates the manufacture of the tub with the flaring shape desired since the flexibility imparted thereby enables the production of the tub from a rectangular blank.

The hub bottom is here shown as formed with a vertical axial depending sleeve 165 secured to the bottom 160 and braced by the false bottom 166, said sleeve being formed at its lower end with an outturned flange 167 connected by means of a flexible gasket 168 to the outturned flange of an intermediate sleeve 170 which loosely surrounds the riser 142 and has at its upper end a socket 171 for the upper end of the shaft 155. This arrangement permits the tub to gyrate freely without vibration in case the load therein be unbalanced in any way.

The washing mechanism in this embodiment comprises an upright cylinder 175 having at its lower end a constricted portion 176 terminating in an aperture 177 defining a seat for a rubber ball 178 to which is attached a vertical stem 179. Slidably mounted inside this cylinder is a plunger 180 having a central hollow hub 181 in which the stem 179 is loosely received. At its upper end the stem terminates in a head 182 between which and the plunger is interposed a spring 183. A valve 185 controls the flow of liquid from the pump casing to this hydraulic washing device.

The operation of this last described washing machine is as follows: the tub is filled with washing liquid in sufficient quantity to overflow through the apertures 163 and form a substantial layer in the bottom of the casing. The motor 10^a being started and the valve 185 being open (the valve 135 being closed) the effect of the pump is to deliver a forceful stream of water of very considerable volume into the cylinder 175. The ball 178 being seated the effect of the water pressure is to elevate the plunger 180, compressing the spring 183 until the upward pressure thereof quickly raises the ball 178 from its seat, whereupon the contents of the cylinder are powerfully ejected upon the articles in the tub by the action both of the inflowing liquid and the weight of the plunger. The weight of the plunger must be sufficient to cause it to fall when the aperture 177 is open, and its weight can be augmented by a spring if desired. This discharge continues until the ball 178 arrives near its seat whereupon the suction causes it to close

quickly whereupon the action is repeated. In this way a pulsating discharge of coherent masses of water are produced which has the effect of thoroughly agitating and pounding the clothes 5 and washing all floating scum through the apertures 163 into the outer casing where they are retained since the pump takes only from the of the turbine in order to reach the central chamber the casing into the pump, passing the vanes 157 10 of the turbine in order to reach the central chamber of the impeller, produces a slow and steady rotation of the tub whereby successive operations of the washing device are applied to an ever-changing portion of the tub contents. The size 15 and number of apertures 163 is so adjusted that the desired amount of liquid remains in the tub at all times during this part of the operation, and the elevation of the tub above the bottom of the casing is such as to accommodate all the 20 liquid therebeneath.

If now the valve 185 be closed, the liquid displaced by the pump impeller can no longer escape, but is turned back upon itself with the production of a very powerful swirling motion adjacent the impeller which acts upon the vanes 157 and readily imparts to the tub a high rate of rotation thereby forcibly ejecting all the liquid through the apertures 163.

While in this last embodiment I have shown the 30 pump impeller and turbine rotor as located inside the same casing for purposes of simplicity, it will be understood that separate casings can be employed therefor as in the other modifications herein shown; and while I have shown the 35 washing effect as produced by the employment of a forceful stream of water, and without the interposition of paddles, blades, bells, beaters or other mechanical accessories, it will be obvious that the pounding effect can be produced if desired in a secondary manner as well as in a primary manner.

Such a hydraulically operated rhythmically moving mechanical pounder is illustrated in Fig. 19 wherein the end of spout 139 is provided with a reciprocating device which converts the energy 45 of the liquid into mechanical reciprocation of an inverted cup 190. This suction cup is carried by a vertical piston rod 191 secured to a piston 192 in a vertical cylinder 193 carried by the hollow head 194 and surrounded by a closed outer shell 195. Formed in this head are two liquid passageways 196 and 197 shown in Figs. 22 and 50 23, one, 196 communicating with the bottom end of the cylinder 193 and the other, 197, communicating with the annular space between the cylinder and shell and thus with the upper end of the cylinder.

Located adjacent the passageways 196 and 197 is a butterfly valve 198 which when in one position establishes communication between the spout 139 and the passage 197 as shown in Fig. 22, meanwhile establishing communication between the other passage 196 and a downwardly facing discharge port 199; or when reversed into the 65 dotted line position shown in Fig. 22 interchanges those connections and causes the spout 139 to communicate with the passage 196 and the passage 197 to communicate with the discharge port 199.

For operating this valve I have shown a kind of crank 200 connected therewith and cooperating with a kind of spool 201 slidably interposed between the lower end of the rod 191 and the fixed bearing 202 carried by the head 194. A 75 pair of spaced flanges 203—203 engages this

crank alternately to shift the valve from one position to the other, while a trip device of suitable construction such as the toggle links 204—204 and spring 205 provides the desired snap action of this spool. Upon the arrival of the rod 191 at the end of its stroke the position of this spool is altered reversing the position of the valve 198 and reversing the direction of motion.

In Fig. 19 I have shown the pump casing 13^a as having its axis horizontal and its rotor shaft 11^a provided with a pulley which is belted to the driving pulley 210 of the motor 211. I have also shown the washing container as having side walls 161 of the same shape as in Fig. 13, but removably resting on a circular tray 212, the bottom of which is provided with turbine blades 213 located to receive the liquid discharge from a fixed nozzle 214 projecting into the side of the casing 1^c from the upright pipe 137 which leads from the outlet of the motor casing 13^a to the spout 139, the latter being provided with a control valve 185 whereby the action of the washing mechanism can be arrested. While the valve 185 is open the discharge from the nozzle 214 is much weakened with the result that the tub revolves comparatively slowly, although sufficiently to bring all parts thereof repeatedly under the action of the pounder. When the valve 185 is closed and the action of the pounder thereby arrested, the greatly augmented discharge from the nozzle 214 causes a very rapid rotation of the tub and discharges the liquid centrifugally therefrom in the well known manner.

To support the tray 212 I have shown a hollow upright bearing sleeve 215 rising into the casing 1^c and having a vertical shaft 216 journaled therein and supported by a suitable thrust bearing 217, the upper end of the shaft being provided with a connecting sleeve 218 depending outside of the sleeve 215 and connected to a third sleeve 115 219 depending from the tray with interposition of a flexible washer 220 to permit a certain amount of gyration of the device. It is obvious, of course, that other and simpler or modified supporting, pivoting, controlling, etc. devices can be used.

In all the apparatus herein described the essential considerations are the operation of a washing device of the rhythmically moving type (and sometimes also an extractor of the centrifugal type) by fluid pressure produced by an electrically driven pump carried by and forming a part of the machine itself, regardless of the nature, shape, position or material of the washing devices, regardless of the shape or construction of the centrifuge container, regardless whether the washing and centrifugal actions take place in the same or different compartments, and regardless whether the driving devices be operated by the washing fluid or by a different fluid. The expression "rhythmically operating" is employed as covering all intermittent repetitive means whether they contain mechanical agitators, gyroscopes, pounders, or beaters, or whether they operate solely by the intermittent discharge of liquid, as for example in the forms shown in Figs. 6, 7, 8 and 13; and whether their motion be oscillatory or reciprocatory, rectilinear or curvilinear; and regardless of the speed or violence of the pulsating movement. It is also desirable, but not at all necessary, that the motor be vertical and that packing boxes be avoided by locating the motor above liquid level. Such apparatus can be made much more cheaply than other apparatus, it can be used where water under pressure is not available, and without waste of water where it is available, while the peculiar nature of the 145 150

- driving mechanism entails a minimum of danger to unskilled persons owing to the entire absence of gears and positive driving devices. I have chosen widely dissimilar structures as illustrative embodiments of my inventive idea to demonstrate that I do not limit myself to any narrow interpretation thereof, since many changes are intended to be comprehended within my various claims which I request may be construed each independently of limitations contained in other claims.
- Having thus described my invention what I claim is:
1. In a combined washing machine and centrifuge, in combination, a rotatable tub, a liquid containing casing surrounding said tub, a branched conduit, a pump for causing circulation of fluid through said conduit, a fluid-pressure turbine operatively connected to said tub, fluid-pressure operated means operatively associated with one branch of said conduit for washing the articles in said tub, said turbine being operatively associated with the other branch of said conduit, and means for controlling the distribution of the effluent from said pump to the respective branches and thereby the operation of said turbine and washing means.
  2. In a combined washing machine and centrifuge, in combination, a rotatable tub, a casing surrounding said tub, fluid-pressure operated clothes washing appliances operatively associated with the tub contents, a motor, and driving means for said washing appliances and said tub including a fluid-pressure creating device operatively connected to said motor, a fluid-pressure rotating device operatively connected to said tub, and means including a valve for controlling the flow of fluid from said fluid-pressure creating device to said washing appliances or to said rotating device to spin said tub.
  3. In a clothes washing machine, the combination with a tub having a washing compartment, of a hydraulic pump located below the bottom level of said compartment, a clothes agitating device in the washing compartment of said tub, driving means for said device operatively connected to the outlet of said pump, an electric motor for driving said pump, a vertical tube communicating with said pump and having an open upper end located on a higher level than that of said pump or said driving means, and means extending through said tube for effecting a driving connection between said pump and motor, said tube serving to prevent the escape of liquid around the driving connection of said pump.
  4. A combined washing and extracting machine, comprising a receptacle for clothes and liquid, an electric motor, a centrifugal pump operatively connected thereto, means for converting the power of the moving fluid issuing from said pump into rhythmic agitation of the contents of said receptacle, a turbine operatively connected to said receptacle and means for converting said moving fluid from said first means and directing the same to said turbine.
  5. In a combined clothes washing machine and extractor, in combination, a container for clothes and washing liquid, a hydraulic device for rotating said container to discharge the liquid contents thereof, reversely acting hydraulic means for agitating the clothes and liquid in said container, means including a pump and motor carried by and constituting a part of said washing machine for generating the hydraulic pressure for operating both said rotating means and said reversely acting means, and a valve controlling the liquid flow from said pump to said reversely acting means.

CERTIFICATE OF CORRECTION.

Patent No. 1,932,246.

October 24, 1933.

JAMES B. KIRBY.

It is hereby certified that error appears in the printed specification of the above numbered patent requiring correction as follows: Page 5, line 8, strike out the words "of the turbine in order to reach the central cham—" and insert instead bottom of that casing. The flow of liquid from; and that the said Letters Patent should be read with this correction therein that the same may conform to the record of the case in the Patent Office.

Signed and sealed this 6th day of February, A. D. 1934.
